Primary Examiner — Selina Sikder(74) *Attorney, Agent, or Firm* — Birch, Stewart, Kolasch & Birch, LLP(57) **CLAIM**

The ornamental design for a smart key for automobiles, as shown and described.

DESCRIPTION

FIG. 1 is a perspective view of a smart key for automobiles showing our new design; FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a reference view showing the state that during operation, the phone number or message is shown on the right side display; and,

FIG. 9 is a reference view showing the state that the earset on the upper part can be detached.

The broken lines in FIG. 8 show environmental structure only and form no part of the claimed design.
